UNITED STATES PATENT OFFICE

LAWRENCE L. NEEBE, OF WOODBURY, NEW JERSEY

FOOTPLATE FOR LOCOMOTIVES

Application filed August 4, 1931. Serial No. 555,099.

My invention relates to certain improvements in the rear foot plate of a locomotive.

The object of the invention is to make the foot plate structure in a single casting having forwardly extending arms, to which the side frames of the locomotive are secured, lateral arms carrying the upper rocker bearings and the furnace bearer, and also having a laterally extending bracket on one side, on which the feed pump is supported. At the rear end of the structure are pads for the cab brackets.

In the accompanying drawings:

Fig. 1 is a plan view of the improved rear foot plate;

Fig. 2 is a side view;

Fig. 3 is a rear view;

Fig. 4 is a longitudinal sectional view on the line 4—4, Fig. 1; and

Fig. 5 is a transverse sectional view on the line 5—5, Fig. 1.

Referring to the drawings: 1 is the foot plate, which is made in a single casting having two longitudinal members 2 extending the full length of the foot plate and terminating at the forward end in arms 3. Each arm has an upper flange 4 and a lower flange 5, which are located between side frames 6, shown by dotted lines in Fig. 1, and these side frames are secured to the foot plate by bolts which pass through the perforations 7 in the body portion of the arms or other fastening means. By this construction the foot plate is securely fastened to the side frame of the locomotive. 8 is a horizontal web which connects the longitudinal members 2—2 and this web is perforated at 10, so that access may be had to the coupling member. The web 8 is cut away at the forward end, leaving tapered portions 9—9, which reinforce the arms 3 to which the side members of the frame are secured. At the rear of the foot-plate is a transverse bumper plate 11, which has an upwardly projecting flange 12 and a projecting rib 13. The flange 12 has pads to which are secured the cab brackets, the brackets resting on the ribs 13. The cab brackets are secured to the upstanding ribs 12 by bolts or other suitable fastenings.

Extending laterally from the longitudinal

members 2 are arms 14, in which are the bearings 15 for the upper rockers of the trailing truck, and mounted on these arms are the furnace bearers 16, and secured to these bearers are the furnace bearer plates 17, shown by dotted lines in Fig. 1 and full lines in Figs. 2 and 3.

Projecting from one side of the structure is a bracket 18, which supports the feed pump and on the upper surface of this bracket are pads 19 on which the pump is mounted. The bolts which fasten the pump to the brackets extend through holes 20 in the pads, as clearly shown in Fig. 1. The bracket is reinforced by a series of ribs. The forward rib 21 extends to the extreme outer end of the bracket, while the rear rib 22 extends only part way so as not to interfere with the pump, and the intermediate ribs 23 only extend to a point in line with the inner ends of the pads 19. On the underside of the bracket are shallow ribs 24 which extend to the extreme end of the brackets and also extend under the plate 25, forming the bottom of the opening 26 for the coupling member, and projecting upwardly from this plate is a lower bearing 27, in which is an opening 28 for the coupling pin. A plate 29 forms the top of the opening 26 and has a bearing 30 in which is an opening 31 in line with the opening 28 for the coupling pin (Fig. 4).

32 is a transverse vertical web extending from one longitudinal member 2 to the other longitudinal member and is connected to the horizontal web 8 and the plate 29, and the lower bearing 27. A rib 33 projects from this plate in the lower edge of the longitudinal members 2 and is tapered at its outer end in the same manner as the tapered portions 9 of the horizontal web 8. The vertical flanges 34 of the upper rocker bearing are perforated at 35 to lighten the structure.

It will be seen by the above construction that a very substantial foot plate is provided for a locomotive in which a number of the elements are cast integral therewith, and especially the support for the feed pump which projects at one side of the structure between the arms 14 and the bumper plate 11.

I claim:

100

1. The combination in a foot plate for a locomotive, of two longitudinal side members extending the full length of the plate, the forward end of the side members being flanged at the top and bottom and having perforations for securing bolts by which the frame is secured to the side frames of the locomotive; a substantially horizontal web extending from one side member to the other and perforated above the coupling pin bearings, and cut away at the forward end, forming tapered reinforcing flanges for the extending forward ends of the longitudinal members; and a bracket extending laterally from one of the side members for a feed pump.

2. The combination in a foot plate for a locomotive, of two longitudinal side members extending the full length of the plate, the forward end of the side members being flanged at the top and bottom and having perforations for securing bolts by which the frame is secured to the side frames of the locomotive; a substantially horizontal web extending from one side member to the other and perforated above the coupling pin bearings, and cut away at the forward end, forming tapered reinforcing flanges for the extending forward ends of the longitudinal members; and a bracket extending laterally from one end of the longitudinal members for a feed pump, said bracket having pads on which the said pump is mounted and having reinforcing webs extending from the bracket to the forward side member.

3. A foot plate for a locomotive, made in a single casting and having longitudinal side members; a horizontal web connecting the members; a vertical web depending from the horizontal web; upper and lower plates spaced apart and forming the bottom and top of a coupling recess; bearings in each plate for coupling pins, the horizontal web being open at the top to allow access to the coupling pin; brackets at each side of the structure forming the upper rocker bearings; and a bracket extending from one of the longitudinal members back of one of the brackets for a feed pump.

4. A foot plate for a locomotive made in a single casting having two longitudinal side members spaced apart and extending at the forward end, and perforated for the reception of the bolts which secure the side frames of the locomotive to the said foot plate; and brackets extending from each side of the foot plate, forming upper rocker bearings; a transverse plate at the rear of the foot plate, having an upwardly extending flange to which the cab brackets are secured, and a pump bracket extending from one side of the structure.

5. A foot plate for a locomotive, made in a single casting and having longitudinal side members terminating in arms to which the

side frames of the locomotive are secured, one of said side members having a bracket projecting laterally from one side member near the lower portion of said member, said bracket being designed to support a feed pump.
